FLUID OPERATED PUMP CONTROL SYSTEM
Clarence J. Coberly, San Marino, Calif., assignor to Kobe,
Inc., Huntington Park, Calif., a corporation of California

Filed Dec. 5, 1960, Ser. No. 73,565
13 Claims. (Cl. 121—158)

The present invention relates in general to fluid operated bottom hole pumps for oil wells and, more particularly, to an improved control system for the engine valve means of such a pump.

As background, a fluid operated pump of the type to which the invention relates includes interconnected engine and pump piston means which are reciprocated by applying fluid pressure forces to the engine piston means in opposite directions alternately, whereupon the pump piston means pumps production fluid from the well to the surface. The engine and pump piston means are movable in at least one direction by an engine-operating fluid pressure differential of $P_1 - P_2$ applied to the engine piston means, P_1 being the supply pressure of an operating fluid, such as relatively clean crude oil, and P_2 being the discharge pressure thereof. In many instances, the engine-operating pressure differential $P_1 - P_2$ is utilized to displace the engine and pump piston means in both directions, but this is not essential to the invention.

The various pressures applied to the engine piston means to reciprocate it and the pump piston means connected thereto are controlled by an engine valve means which includes an engine valve reciprocable between two operating positions. In one of its operating positions, the engine valve causes movement of the engine and pump piston means in one direction, and, in its other operating position, it causes movement thereof in the opposite direction. The engine valve means may be incorporated in the engine and pump unit, as disclosed in my Patent No. 2,311,157, granted February 16, 1943, or it may be incorporated in a separate engine valve unit spaced from the engine and pump unit, as disclosed, for example, in my Patent No. 2,949,857, granted August 23, 1960.

Conventionally, the engine valve of a fluid operated pump is reciprocated by applying thereto in opposite directions alternately the same fluid pressure differential $P_1 - P_2$ used to displace the engine and pump piston means. Since $P_1 - P_2$ may vary widely from one well installation to another, it is impossible under such conditions to design a single engine valve means which will work in all well installations. Actually, a large number of different engine valve means must be available to satisfy a wide $P_1 - P_2$ range.

Another problem arises because of the fact that the physical properties of the operating fluid vary widely, both because such physical properties may be inherently different from one operating fluid to another, and because the physical properties of a given operating fluid vary widely with different pressure and temperature conditions encountered in different wells. Viscosity is the property which is subject to the greatest variation from one operating fluid to another, and the viscosity of a given operating fluid varies widely depending upon the temperature and pressure conditions encountered in different well installations. For example, a viscosity range of one to as high as ten thousand centistokes may be encountered with different operating fluids and different well conditions. No single conventional engine valve means can operate satisfactorily throughout such a wide viscosity range.

Thus, with the wide ranges of engine-operating fluid pressure differentials and operating fluid viscosities encountered, it has heretofore been necessary to utilize a substantial number of different engine valve means each

2

capable of accommodating only a narrow range of conditions.

With the foregoing in mind, a primary object of the present invention is to provide an engine valve means wherein the engine valve is moved between its two operating positions by a valve-operating fluid pressure differential Δp which is completely independent of P_1 and P_2 and which may be varied to compensate for viscosity variations. With this construction, a single engine valve means may be utilized for any pressure and viscosity conditions that may be encountered, which is an important feature of the invention.

More particularly, an important object of the invention is to provide a valve-operating fluid pressure differential which is small as compared to the $P_1 - P_2$ values normally encountered, which is independent of P_1 and P_2 , and which is constant except for any variations that may be required to accommodate viscosity variations. An important advantage of an engine valve means utilizing a Δp which is small as compared to the $P_1 - P_2$ values normally encountered is that such an engine valve means can be incorporated in any installation having a value of $P_1 - P_2$ at least equal to the necessary Δp .

Another important object of the invention is to provide a valve operating pressure falling between P_1 and P_2 and differing from either P_1 or P_2 by an amount Δp which is small as compared to the $P_1 - P_2$ values normally dealt with. In other words, an object of the invention is to provide a valve operating pressure which is equal either to $P_1 - \Delta p$, or to $P_2 + \Delta p$, where Δp is independent of P_1 , or of P_2 , and is normally small compared to $P_1 - P_2$.

Still another important object of the invention is to provide an engine valve means having means for varying Δp as a function of the viscosity of the operating fluid so that a larger Δp is available with a more viscous operating fluid to compensate for correspondingly larger friction losses in the control passages and orifices of the engine valve means, whereby the effective pressure differential actually applied to the engine valve remains constant.

Since the valve-operating fluid pressure differential Δp utilized to displace the engine valve between its operating positions is thus independent of P_1 and P_2 , is small as compared to the $P_1 - P_2$ values normally encountered, is no greater than the minimum $P_1 - P_2$ value encountered, and is varied as a function of the operating fluid viscosity, it will be apparent that a single engine valve means of the invention will accommodate wide ranges of viscosities and P_1 and P_2 values since the effective pressure differential actually applied to the engine valve is constant.

Another object of the invention is to utilize a value of Δp permitting the use of turbulent flow orifices for controlling the valve functions which are of practical sizes.

It is another object of the invention to provide an engine valve means of the foregoing nature having means for sensing the load on the engine piston means and for throttling the engine valve at any time that the load on the engine piston means is below normal.

The foregoing objects, advantages, features and results of the present invention, together with various other objects, advantages, features and results thereof which will be evident to those skilled in the fluid operated pump art in the light of this disclosure, may be achieved with the exemplary embodiments of the invention described in detail hereinafter and illustrated in the accompanying drawings, in which:

FIGS. 1 and 2 are semidiagrammatic vertical sectional views of a fluid operated pump which embodies the engine valve means of the invention, various parts being shown in different operating positions in the two figures;

FIG. 3 is a semidiagrammatic view, partially in vertical

section and partially in elevation, which is similar to FIGS. 1 and 2 but which illustrates another embodiment of a fluid operated pump of the invention; and

FIGS. 4 and 5 are fragmentary, semidiagrammatic, vertical sectional views showing alternative embodiments of parts of the engine valve means of the invention.

Introduction

In the drawings, the fluid operated pump incorporating the engine valve means of the invention is shown as comprising a fluid operated engine and pump unit and a separate engine valve unit located in side-by-side relation, both units being adapted to be circulated into and out of the well hydraulically. Thus, the construction shown corresponds to that of my aforementioned Patent No. 2,949,857. However, it will be understood that the fluid operated engine and pump and the engine valve means may also be incorporated in a single unit, as shown, for example, in my aforementioned Patent No. 2,311,157. Also, the invention may be embodied in a fluid operated pump of the set type, as opposed to a fluid operated pump of the free type having one or more components hydraulically circulatable into and out of the well. Furthermore, while the drawings illustrate a closed system, wherein the spent operating fluid at the discharge pressure P_2 is returned to the surface independently of the production fluid from the well, it will be understood that the invention may also be utilized in an open system, wherein the spent operating fluid and the production fluid are mixed.

Pump of FIGS. 1 and 2

Turning now to FIGS. 1 and 2 of the drawings, the numeral 10 designates a bottom hole housing having therein, in side-by-side relation, a chamber 12 for a fluid operated engine and pump unit 14 and a chamber 16 for a separate engine valve means or unit 18 of the invention. The engine and pump unit 14 is movable between its operating position in the chamber 12 and the surface through a tubing 20 for conveying production fluid from the well to the surface. Similarly, the engine valve unit 18 is movable between an operating position in the chamber 16 and the surface through a supply tubing 22 for delivering operating fluid at the supply pressure P_1 to the engine valve unit 18 and ultimately to the engine and pump unit 14. Also connected to the bottom hole housing 10 is a return tubing 24 for conveying spent operating fluid at the pressure P_2 to the surface.

Engine and Pump Unit 14

The engine and pump unit 14 includes a housing 26 having a tapered lower end which is in engagement with an annular seat 28 on the bottom hole housing 10 when the unit 14 is in its operating position. A passage 30 in the housing 10 interconnects the return tubing 24 and the chamber 12 above the annular seat 28 so that, by reversing the flow of operating fluid through the return tubing 24, as is well known in the art, the engine and pump unit 14 may be circulated upwardly through the production tubing 20 to the surface.

Reciprocable vertically in the housing 26 is a tubular engine and pump plunger 32 constituting the hereinbefore-mentioned interconnected engine and pump piston means. More particularly, the tubular plunger 32 includes a tubular upper rod 34 reciprocable in a bore 36 in the housing 26, a tubular engine piston 38 connected to the lower end of the upper rod 34 and reciprocable in an engine cylinder 40 in the housing 26, a tubular lower rod 42 connected to the lower end of the engine piston and reciprocable in a bore 44 in the housing 26, and a tubular pump piston 46 connected to the lower end of the lower rod 42 and reciprocable in a pump cylinder 48 in the housing 26. As will be explained hereinafter, the plunger 32 is reciprocated by applying P_1-P_2 to the engine piston 38 in opposite directions alternately, this being accomplished by the engine valve unit 18 under the

control of upper and lower annular control grooves 50 and 52 in the upper rod 34. The tubular plunger 32 carries a working valve 54 which prevents downward flow through an axial passage 56 in the plunger. The lower end of the housing 26 of the engine and pump unit 14 is provided with an inlet 58 in communication with an inlet 60 in the bottom hole housing 10 when the unit 14 is in its operating position. Downward flow out of the pump cylinder 48 is prevented by a standing valve 62 in the inlet 58, and drainage of the tubing system when the engine and pump unit 14 is unseated is prevented by a standing valve 64 in the inlet 60. The upper end of the pump cylinder 48 is connected to the inlet 58 at a point below the standing valve 62 by ports 66 in the housing 26, an annular clearance 68 between the housings 26 and 10, and ports 70 in the housing 26.

As will be apparent, when P_1-P_2 is applied to the engine piston 38 in the downward direction, the plunger 32 moves downwardly and the working valve 54 opens while the standing valves 62 and 64 close, this condition being shown in FIG. 1 of the drawings. As shown in FIG. 2, when P_1-P_2 is applied to the engine piston 38 in the upward direction, the plunger 32 moves upwardly and the working valve 54 closes while the standing valves 62 and 64 open. Production fluid is displaced upwardly into the production tubing 20 during both the upward and downward strokes of the plunger 32. As will readily be recognized by those skilled in the art, the engine and pump unit 14 provides a differential double acting pump in which the differential action is obtained entirely with the pump piston 46, the engine piston 38 operating as a full double acting engine.

Engine Valve Unit 18

Turning now to the engine valve unit 18 of the invention, it includes a housing 72 having a tapered lower end which engages an annular seat 74 on the bottom hole housing 10 when the engine valve unit is in its operating position. A passage 76 in the bottom hole housing 10 serves to apply fluid pressure to the lower end of the engine valve unit 18 from the return tubing 24 to circulate the engine valve unit upwardly through the supply tubing 22 to the surface when the flow through the return tubing is reversed. As pointed out in my aforementioned Patent No. 2,949,857, the two units 14 and 18 may be circulated out of the well simultaneously, or separately.

Vertically reciprocable in the engine valve housing 72 is an engine valve 78 which includes a differential-area actuator 80, the engine valve being reciprocable in minor and major bores 82 and 84 in the engine valve housing. The engine valve 78 is a four-way valve capable of alternately applying P_1 and P_2 to the upper end of the engine piston 38 and of simultaneously alternately applying P_2 and P_1 , respectively, to the lower end of the engine piston. Thus, the engine-operating fluid pressure differential P_1-P_2 is applied to the engine piston 38 in opposite directions alternately to reciprocate the plunger 32.

Considering how the foregoing is accomplished, the engine valve 78 includes two cylindrical lands 86 and 88 which are disposed in the minor bore 82 and the ends of which have V-shaped throttling grooves therein to provide for gradual opening and closing of the engine valve, as explained in my Patent No. 2,311,157. When the engine valve 78 is in its lower operating position, as shown in FIG. 1 of the drawings, the upper land 86 is disposed below a passage 90 connecting the minor bore 82 to the upper end of the engine cylinder 40. The upper end of the minor bore 82 communicates with the supply tubing 22 so that, under these conditions, the supply pressure P_1 is applied to the upper end of the engine piston 38. At the same time, communication between the lower end of the engine cylinder 40 and the return tubing 24 is established by way of a passage 92, the space between the upper and lower lands 86 and 88 of the engine valve 78, and a passage 94. Thus, the discharge pressure P_2

in the return tubing 24 is applied to the lower end of the engine piston, wherefore the engine-operating fluid pressure differential $P_1 - P_2$ is applied to the plunger 32 in the downward direction.

Turning to FIG. 2 of the drawings, when the engine valve 78 is in its upper operating position, the discharge pressure P_2 in the return tubing 24 is applied to the upper end of the engine piston 38 through the passage 92, the space between the upper and lower lands 86 and 88 of the engine valve, and the passage 90. At the same time, the supply pressure P_1 in the supply tubing 22 is applied to the lower end of the engine piston 38 by way of a passage 96 interconnecting upper and lower portions of the minor bore 82, a space between the lower land 88 of the engine valve and the actuator 80, and the passage 94. Thus, the engine-operating fluid pressure differential $P_1 - P_2$ is so applied to the engine piston 38 as to move the plunger 32 upwardly.

Thus, when the engine valve 78 is in its lower operating position, the lands 86 and 88 are in such positions that they apply $P_1 - P_2$ to the engine piston 38 in the downward direction. Conversely, when the engine valve 78 is in its upper position, the lands 86 and 88 are in such positions that they apply $P_1 - P_2$ to the engine piston 38 in the upward direction.

Considering now the manner in which the engine valve 78 is displaced from one of its operating positions to the other, it will be noted first of all that the upper end of the engine valve, i.e., the upper end of the upper land 86 thereof, is constantly exposed to the supply pressure P_1 in the supply tubing 22. The actuator 80 includes a piston 98 reciprocable in the major bore 84 and having at its upper end an annular area preferably equal to the area at the upper end of the engine valve 78 which is constantly exposed to the supply pressure P_1 . The annular area of the upper end of the piston 98 is constantly exposed to a valve operating pressure of $P_1 - \Delta p$ which is produced in a manner to be described hereinafter. As hereinbefore outlined, Δp is small as compared to the $P_1 - P_2$ values normally encountered and is independent of P_1 and P_2 .

Thus, the engine valve 78 is constantly biased downwardly by the supply pressure P_1 and the valve operating pressure $P_1 - \Delta p$ applied to equal areas of the engine valve, the supply pressure P_1 acting on the upper end of the engine valve and the valve operating pressure $P_1 - \Delta p$ acting on the upper end of the piston 98. In order to produce movement of the engine valve 78 upwardly into its upper position, the supply pressure P_1 is applied to the lower end of the piston 98, the lower end of this piston having an area preferably equal to twice the annular area of the upper end thereof. Conversely, in order to move the engine valve 78 downwardly into its lower position, the valve operating pressure $P_1 - \Delta p$ is applied to the lower end of the piston 98. It will be apparent that, with the area relationships outlined, the upward and downward forces applied to the engine valve 78 in moving it to its upper and lower positions are equal simply to Δp , minus friction losses.

Considering how P_1 and $P_1 - \Delta p$ are alternately applied to the lower end of the piston 98, when the engine and pump plunger 32 reaches the upper end of its travel, as shown in FIG. 1 of the drawings, the lower control groove 52 in the upper rod 34 bridges two control passages 100 and 102 leading to the upper rod bore 36. The control passage 100 communicates with the major bore 84 adjacent the lower end thereof through an orifice 104 of the sharp-edge type. The control passage 102 communicates with the upper end of the major bore 84, where, as will be described, the valve operating pressure of $P_1 - \Delta p$ is constantly available. Under these conditions, the valve operating pressure of $P_1 - \Delta p$, less friction losses, is applied to the lower end of piston 98, whereupon the engine valve 78 moves downwardly into its lower position to initiate downward movement of the engine and pump

plunger 32 under the influence of the engine-operating fluid pressure differential $P_1 - P_2$.

On the other hand, when the engine and pump plunger 32 reaches the lower end of its travel, as shown in FIG. 2, the upper control groove 50 in the upper rod 34 bridges two control passages 106 and 108 leading to the upper rod bore 36. The control passage 106 communicates with the upper end of the minor bore 82 and thus contains the operating fluid at the supply pressure P_1 . The control passage 108 leads to an intermediate portion of the major bore 84 and, when the engine valve 78 is in its lower position, communicates with the lower end of the piston 98 through a wide external annular channel 110 in the piston 98, through another orifice 104, identical to the orifice 104 mentioned previously, and formed in the piston 98, and through an axial passage 112 in the engine valve actuator 80. Under these conditions, the supply pressure P_1 , less friction losses, is applied to the lower end of the piston 98 to initiate upward movement of the engine valve 78 toward its upper position preparatory to applying the engine-operating fluid pressure differential $P_1 - P_2$ to the engine and pump plunger 32 in the upward direction.

In addition to the control orifices 104, one formed in the engine valve housing 72 and the other in the actuator piston 98, the actuator 80 is provided therein with two vertically spaced control orifices 114 and two vertically spaced control orifices 116, all of the sharp-edge type and all communicating with the axial passage 112 in the actuator. When the engine valve 78 is in its lower position, the orifices 114 and 116 are positioned as shown in FIG. 1 relative to the major and minor bores 82 and 84. When the engine valve 78 is in its upper position, these orifices are positioned as shown in FIG. 2 relative to the minor bore 82 and an annular clearance 118 which is spaced upwardly from the upper end of the major bore 84.

The purpose of the control orifices 104, 114 and 116 is to cause the engine valve 78 to move from each of its operating positions to the other at three successively different speeds. The first speeds of the engine valve 78 in its two directions of movement are controlled by the orifices 104, the second speeds by the orifices 114, and the third speeds by the orifices 114 and 116 in parallel. Such three-speed engine-valve movement is explained in detail in my aforementioned Patent No. 2,311,157, the disclosure of which is incorporated by reference so that a complete explanation herein is unnecessary.

The foregoing describes the manner in which the engine valve 78 is shifted in both directions by the valve-operating fluid pressure differential Δp , less friction losses, as the result of alternately applying the supply pressure P_1 and the valve operating pressure $P_1 - \Delta p$ to the lower end of the actuator piston 98. The manner in which the valve operating pressure $P_1 - \Delta p$ is produced will now be considered.

Valve Operating Pressure Control

The engine valve housing 72 provides a cylinder, having major and minor bores 120 and 122, for a control valve 124 which includes a plunger having major and minor pistons 126 and 128 respectively disposed in the major and minor bores 120 and 122. The valve 124 controls flow of the operating fluid from the upper portion of the minor bore 122, which upper portion, as will become apparent, acts as a source 130 of operating fluid at the valve operating pressure $P_1 - \Delta p$, to the return tubing 24 by way of a passage 132. The source 130 of $P_1 - \Delta p$ communicates with the upper end of the major bore 84 for the actuator piston 98 through a passage 134, thereby supplying operating fluid at the valve operating pressure to the upper end of the major bore 84.

Considering the forces acting on the control valve 124, it is biased toward its closed position, wherein it prevents flow from the source 130 to P_2 by way of the passage 132, by the operating fluid at the supply pressure P_1 applied to the lower end of the major piston 126 through a passage 136 connected to the passage 96. The valve 124 is biased toward its open position, wherein it permits the

discharge of pressure from the source 130 to P_2 , by the pressure $P_1 - \Delta p$ acting on the upper end of the minor piston 128 and by a spring 138.

Considering the action of the control valve 124 as thus far described, it will be apparent that the spring 138 determines the magnitude of the valve-operating fluid pressure differential Δp . In other words, the spring 138 maintains the valve 124 in such a position as to maintain the pressure in the source 130 substantially constant at $P_1 - \Delta p$, the spring, in effect, subtracting the pressure increment Δp from P_1 . If the pressure in the source 130 tends to rise above $P_1 - \Delta p$, the valve 124 moves toward a more open position to dissipate the excess pressure to P_2 by way of the passage 132. On the other hand, if the pressure in the source 130 tends to fall below the value $P_1 - \Delta p$, the valve 124 moves toward a more closed position to permit the pressure in the source 130 to build up to $P_1 - \Delta p$ again. In this connection, it should be pointed out that there is a constant leakage flow of operating fluid from the annular clearance 118 around the valve actuator 80 into the upper end of the major bore 84 for the actuator piston 98, the annular clearance 118 always containing operating fluid at the supply pressure P_1 as the result of the presence of the passage 96. This leakage flow from the annular clearance 118 into the upper end of the actuator piston bore 84 takes place through the normal working clearance between the actuator 80 and the portion of the minor bore 82 lying between the annular clearance 118 and the major bore 84. This leakage path is symbolized in FIGS. 1 and 2 of the drawings by a restricted passage 140 which, of course, does not actually exist. Since the actuator piston bore 84 is connected to the source 130 by the passage 134, the symbolic leakage passage 140 provides a means of replenishing any pressure loss in the source 130 below $P_1 - \Delta p$.

The spring 138 is selected to provide the desired Δp for application to the engine valve 78. For example, it has been found that selecting a spring 138 which will produce a Δp of from 500 to 1,000 p.s.i. gives excellent results. Thus, assuming a spring 138 which will provide a Δp of 1,000 p.s.i., and assuming that the pumping conditions are such as to make P_1 and P_2 10,000 p.s.i. and 5,000 p.s.i., respectively, it will be seen that the engine valve 78 is operated by alternately applying to the lower end of the actuator piston 98 the supply pressure P_1 of 10,000 p.s.i. and a valve operating pressure $P_1 - \Delta p$ equal to 9,000 p.s.i. Under such conditions, which are more or less typical, the engine valve 78 is operated by a Δp which is quite small as compared to the engine-operating fluid pressure differential of $P_1 - P_2$, the latter being 5,000 p.s.i. under the conditions specified. Furthermore, Δp is completely independent of P_1 and P_2 . For example, in an installation where P_1 is 5,000 p.s.i. and P_2 is 2,500 p.s.i., Δp will still be 1,000 p.s.i. under the conditions outlined. Thus, with the present invention, the same engine valve 78 may be used throughout a wide range of P_1 and P_2 values since the effective pressure differential actually applied to the engine valve remains constant.

In general, the desired Δp can be obtained as long as $P_1 - P_2$ is at least equal to the desired value. In relatively shallow wells, where column pressures are relatively low, Δp may approach $P_1 - P_2$. In deeper wells, however, Δp becomes relatively small as compared to $P_1 - P_2$. Generally speaking, Δp will always be at least slightly less than $P_1 - P_2$.

Thus, the addition of the pressure control valve 124 to the engine valve 78 in the environment set forth insures that the engine valve can be utilized throughout a wide range of pressures with no change in its performance since it is always operated by the same effective pressure differential. Thus, it is not necessary to supply different engine valves 78 for different pressure conditions, which is an important feature of the invention.

Alternative Valve Operating Pressure Control

Instead of operating the engine valve 78 by applying

thereto the supply pressure P_1 and a valve operating pressure lower than P_1 by an amount Δp , the engine valve can be operated by applying thereto the discharge pressure P_2 and a valve operating pressure higher than P_2 by an amount Δp . In other words, instead of subtracting a relatively small amount from P_1 to obtain a valve operating pressure, a valve operating pressure can be obtained by adding a relatively small amount to P_2 . The structure for accomplishing this is shown in FIG. 5 of the drawings.

Referring thereto, the numeral 142 designates an engine valve housing having therein a cylinder 144 for a control valve 146 which includes a piston 148. The upper end of the cylinder 144 constitutes a source 150 of a valve operating pressure of $P_2 + \Delta p$. The valve 146 controls flow of the operating fluid into the source 150 from a passage 152 which communicates with a source, not shown, of the operating fluid at the supply pressure P_1 . Considering the forces acting on the valve 146, it is biased downwardly toward its closed position by the valve operating pressure $P_2 + \Delta p$ acting on the upper end of the piston 148. The valve 146 is biased upwardly toward its open position by the discharge pressure P_2 acting on the lower end of the piston 148 through a passage 154, and by a spring 156 which is selected to give the desired value of Δp . As will be apparent, if $P_2 + \Delta p$ becomes too high, the valve 146 moves toward its closed position. On the other hand, if $P_2 + \Delta p$ becomes too low, the valve 146 moves toward its open position. The net result is that the pressure in the source 150 is maintained substantially constant at $P_2 + \Delta p$.

The valve operating pressure in the source 150 is applied to an engine valve, not shown, similar to the engine valve 78 through a passage 158. It will be understood that, in this instance, the engine valve is moved between its operating positions by applying P_2 and $P_2 + \Delta p$ to equal and opposite areas in an alternating manner, just as P_1 and $P_1 - \Delta p$ are applied to equal and opposite areas of the engine valve 78 in an alternating manner.

Viscosity Compensation

In general, the present invention provides means for increasing the valve-operating fluid pressure differential Δp , above the Δp value produced by the spring 138, as a function of the viscosity of the operating fluid in order to compensate for the increased pressure drops through the various control passages and control orifices associated with the engine valve actuator 80. In other words, the object is to progressively increase Δp at the source 130 sufficiently as the viscosity of the operating fluid increases that the effective fluid pressure differential actually applied to the engine valve 78 remains constant, thereby offsetting the increasing pressure drops in the various control passages and control orifices resulting from an increasing operating fluid viscosity.

To accomplish the foregoing, the invention adds to the force applied to the pressure control valve 124 by the spring 138 a fluid pressure force which increases as a function of the operating fluid viscosity to provide a Δp which similarly increases with increasing viscosity. The amount that the fluid pressure force added to the spring force increases with an increased operating fluid viscosity is so selected as to make the effective fluid pressure differential actually applied to the engine valve 78 the same at the increased viscosity as it was at the lower viscosity.

More particularly, it will be noted that the passage 136, which contains operating fluid at the supply pressure P_1 , is connected to the upper end of the major bore 120 through an orifice 160 of the sharp-edge, turbulent flow type, the flow through such an orifice being substantially independent of viscosity. The point of connection to the upper end of the major bore 120 lies between the orifice 160 and a capillary restriction 162 which connects the orifice 160, and the upper end of the major bore 120, to the passage 132 containing the operating fluid at the dis-

charge pressure P_2 . As is well known, the flow through the capillary restriction 162 is directly proportional to the absolute viscosity of the operating fluid.

With the foregoing construction, a compensating pressure, acting in a direction to open the control valve 124, is applied to the annular area at the upper end of the major piston 126. This compensating pressure has the desired effect of increasing Δp at the source 130 with an increase in the operating fluid viscosity, with the result that a reduction in the actual fluid pressure differential applied to the engine valve 78 with increasing viscosity is avoided. By selecting proper sizes for the sharp edged orifice 160 and the capillary restriction 162, the compensating pressure applied to the annular area at the upper end of the major piston 126 may be varied as a function of viscosity in such a manner as to maintain constant the fluid pressured differential actually acting on the engine valve 78. In other words, increasing pressure losses in the control passages and control orifices associated with the engine valve 78, as the operating fluid viscosity increases, are offset. Thus, the same engine valve unit 18 may be used irrespective of the viscosity of the operating fluid, which is an important feature of the invention.

Considering an illustrative example of the magnitude of the viscosity compensating force which must be added to the force produced by the spring 138, it is typical in an engine valve unit like the unit 18 for the various control passages associated with the engine valve 78 to have a pressure drop therethrough, at an operating fluid viscosity of one centistoke, of only approximately 10% of the total pressure drop through the control passage and the control orifices 104, 114 and 116, the control orifices accounting for 90% of the total pressure drop under such conditions. Since the control orifices are of the sharp-edge type, the pressure drops therethrough do not increase significantly with increasing operating fluid viscosity, the effect of viscosity on such an orifice being negligible from Reynolds numbers of 1,000 to infinity. However, increasing viscosity increases the pressure drops through the control passages approximately as the 0.2 power of the viscosity.

From the foregoing, it can be shown that the ratio of the total pressure drop, through the control passages and control orifices, at a viscosity of 10,000 centistokes, to the total pressure drop at a viscosity of one centistoke, is approximately 1.53:1. Consequently, the fluid pressure differential actually applied to the engine valve 78 can be maintained constant under the foregoing conditions throughout a viscosity range of one centistoke to 10,000 centistokes by so selecting the sizes of the orifice 160 and the restriction 162, and the annular area of the upper end of the major piston 126, that the compensating force added to the force produced by the spring 138 is 53% of the spring force at a viscosity of 10,000 centistokes.

It will be understood, of course, that the foregoing example is merely intended as illustrative and that various factors, such as the relative flow resistances of the control passages and control orifices, determine the magnitude of the compensating force which must be added to the spring force to achieve the Δp necessary to provide a constant effective fluid pressure differential at the engine valve 78 at different viscosities.

Alternative Viscosity Compensator

Instead of locating the orifice 160 and the restriction 162 externally of the control valve 124 as shown in FIGS. 1 and 2 of the drawings, an orifice 164, corresponding to the orifice 160, and a restriction 166, corresponding to the restriction 162, may be incorporated in this valve, as shown in FIG. 4 of the drawings. In this case, the orifice 164 is disposed in a passage through the major piston 126, thus interconnecting the lower end of this piston and the annular area at the upper end thereof. The capillary restriction 166 is formed by a portion of the working

clearance between the minor piston 128 and the wall of the minor bore 122, this portion of the working clearance being connected to the P_2 passage 132 by an annular groove 168 and a passage 170.

It will be understood that the hereinbefore-discussed viscosity compensation principle may also be applied to the construction of FIG. 5 wherein the valve operating pressure is $P_2 + \Delta p$, instead of $P_1 - \Delta p$. Again, the object would be to increase Δp at the source 150 as a function of the operating fluid viscosity.

Governing

The present invention adds to the pressure control and the viscosity compensation for the engine valve 78 a governing means, similar to that of my aforementioned Patent

No. 2,311,157, for limiting the speed of the engine and pump plunger 32 whenever the load thereon falls below a predetermined value, as may occur when free gas is present in the pump cylinder 48, when the pumping rate exceeds the productive capacity of the well, and the like. This governing means is designated generally in FIGS. 1 and 2 of the drawings by the reference numeral 172.

The governing means 172 includes a differential-area pilot valve 174 having major and minor portions 176 and 178 respectively reciprocable in major and minor bores 180 and 182. The upper end of the minor portion 178 has an area of "one" constantly exposed to the discharge pressure P_2 through a passage 184, and the upper end of the major portion 176 has an annular area of "one" constantly exposed to the supply pressure P_1 through a passage 186 communicating with the passages 136 and 96. The lower end of the major portion 176 of the pilot valve 174 has an area of "two" alternately exposed to the supply pressure P_1 and the discharge pressure P_2 through a passage 188 connected to the passage 94. Thus, when the engine valve 78 is in its lower position, as shown in FIG. 1, the discharge pressure P_2 is applied to the lower end of the pilot valve 174 so that this valve occupies its lowermost position. Conversely, when the engine valve 78 is in its upper position, as shown in FIG. 2 of the drawings, the supply pressure P_1 is applied to the lower end of the pilot valve 174 so that it assumes its upper position.

When the pilot valve 174 is in its lower position, as shown in FIG. 1, an external annular channel 190 in the minor portion 178 thereof bridges passages 192 and 194, the former being connected to the control passage 102 and the latter being connected to the lower end of the major bore 84 for the actuator piston 98 of the engine valve 78. However, when the pilot valve 174 is in its upper position, as shown in FIG. 2, another annular channel 196 in the minor portion 178, located below the annular channel 190, bridges the passages 186 and 194. Thus, when the engine valve 78 is in its lower position, the pilot valve 174 is also in its lower position and applies the valve operating pressure $P_1 - \Delta p$ to the lower end of the engine valve actuator piston 98 by way of the passages 192 and 194. On the other hand, when the engine valve 78 is in its upper position, the pilot valve 174 is also in its upper position and applies the supply pressure P_1 to the lower end of the engine valve actuator piston 98 by way of the passages 186 and 194.

Considering another aspect of the governing means 172, the upper land 86 of the engine valve 78 is shorter in the axial direction than the lower land 88 thereof. Consequently, as the engine valve 78 approaches either of its operating positions, the upper land 86 reaches its corresponding fully open position before the lower land 88 does, the corresponding V-shaped throttling grooves in the lower land 88 continuing to throttle flow under such conditions. To illustrate, as the engine valve 78 approaches its upper position, the upper land 86 clears the passage 90 before the lower land 88 clears the passage 94. Consequently, the upper end of the engine cylinder 40 is fully opened to the discharge pressure P_2 by way of the pas-

11

sages 90 and 92 while the flow of operating fluid at the supply pressure P_1 into the lower end of the engine cylinder by way of the passages 96 and 94 is still being throttled by the V-shaped throttling grooves in the lower end of the lower land, this being one of the throttling or governing positions of the engine valve. A corresponding situation exists as the engine valve 78 approaches its lower position, except that the discharge of operating fluid from the lower end of the engine cylinder 40 to P_2 is throttled after the upper end of the engine cylinder has been fully opened to P_1 , this being the other throttling or governing position.

With the foregoing construction, the engine valve 78, its actuator 80 and the pilot valve 174 cooperates to hold the engine valve in one or the other of its aforementioned throttling positions if the load on the engine and pump plunger 32 is below a predetermined value for the corresponding direction of movement of such plunger. In other words, the engine valve 78 stalls in each of its throttling positions until the load on the plunger 32 reaches a predetermined value for the corresponding direction of movement thereof. This action is fully explained in my aforementioned Patent No. 2,311,157 so that a complete description herein is unnecessary.

Briefly, and considering only the case wherein the engine valve 78 has reached its throttling or governing position adjacent the end of its upward movement, the upper end of the engine cylinder 40 is fully open to the discharge pressure P_2 , through the passages 90 and 92, while the lower end of the engine cylinder is only partially open to the supply pressure P_1 through the passages 96 and 94. Under such conditions, the full $P_1 - P_2$ is not applied to the plunger 32 in the upward direction so that this plunger starts to move upwardly slowly. This results in movement of the control channel 50 out of bridging relation with the control passages 106 and 108. In view of this, the engine valve 78 cannot be caused to move upwardly all the way into its upper position by the supply pressure P_1 delivered to the lower end of the actuator piston 98 by way of the control passage 108. Also, since the full supply pressure P_1 is not delivered to the lower end of the engine cylinder 40 through the passage 94, the full supply pressure P_1 is not available in the passage 188 to move the pilot valve 174 upwardly into its upper position. Consequently, the engine valve 78 cannot complete its upward movement and remains stalled in its throttling or governing position.

Ultimately, the load on the engine and pump plunger 32 attains the predetermined value mentioned, whereupon the pressure in the lower end of the engine cylinder 40 begins to build up to the supply pressure P_1 . When this occurs, the full supply pressure P_1 is applied to the lower end of the pilot valve 174, causing this valve to shift upwardly into its upper position. Now, the full supply pressure P_1 is applied to the lower end of the engine valve 78 by way of the passages 186 and 194, whereupon the engine valve completes its upward movement into its upper operating position.

A similar action takes place if there is an insufficient load on the engine and pump plunger 32 as the engine valve 78 approaches its lower operating position.

Pump of FIG. 3

The fluid operated pump illustrated in FIG. 3 of the drawings is similar in many respects to that of FIGS. 1 and 2. As a matter of convenience, therefore, the various components of the pump of FIG. 3 will be identified by reference numerals higher by two hundred than the reference numerals used to designate corresponding components of the pump of FIGS. 1 and 2.

Thus, the pump of FIG. 3 includes a bottom hole housing 210 having a chamber 212 for an engine and pump unit 214 and a chamber 216 which receives therein the same engine valve unit 18 described previously. Connected to the bottom hole housing 210 are production and supply tubings 220 and 222 in communication with the

12

chambers 212 and 216, and also connected to the housing 210 is a return tubing 224.

The engine and pump unit 214 includes a housing 226 engageable with an annular seat 228 and adapted to be unseated by fluid supplied through a passage 230. The engine and pump unit 214 includes a tubular plunger 232 comprising an upper rod 234 reciprocable in a bore 236, an upper piston 238 reciprocable in an upper cylinder 240, a lower rod 242 reciprocable in a bore 244, and a lower piston 246 reciprocable in a cylinder 248. The lower rod 242 is provided therein with external annular control grooves 250 and 252. The tubular plunger 232 carries a working valve 254 in an axial passage 256 therethrough. The housings 226 and 210 are respectively provided with inlets 258 and 260 respectively containing standing valves 262 and 264. A port 266, a longitudinal groove 268 and a port 270 connect the inlet 258 to the upper end of the upper cylinder 240.

The engine and pump unit 214 and the engine valve unit 18 are interconnected by: a passage 290 corresponding to the passage 90, but leading to the upper end of the lower cylinder 248; a passage 294 corresponding to the passage 94 and leading to the lower end of the upper cylinder 240; a control passage 306 corresponding to the control passage 106, but leading to the bore 244; a control passage 308 corresponding to the control passage 108, but leading to the bore 244, the control passages 306 and 308 being bridgeable by the control groove 250; a control passage 300 corresponding to the control passage 100, but leading to the bore 244; a control passage 302 corresponding to the control passage 102, but leading to the bore 244, the control passages 300 and 302 being bridgeable by the control groove 252; a passage 388 connected to the passage 294 and corresponding to the passage 188; and a passage 392 connected to the passage 302 and corresponding to the passage 192.

With the pump of FIG. 3, the supply pressure P_1 and the discharge pressure P_2 are alternately applied to the lower end of the piston 238 by way of the passage 294 and the discharge pressure P_2 and the supply pressure P_1 are simultaneously alternately applied to the upper end of the piston 246 through the passage 290. Thus, the pump of FIG. 3 is a double acting pump in which both of the pistons 238 and 246 serve as the engine piston, or, more accurately, the lower end of the piston 238 and the upper end of the piston 246 serve as the engine piston. The pump of FIG. 3 is also a differential pump in which both of the pistons 238 and 246 cooperate to provide the differential pumping action. Thus, the pump of FIG. 3 is basically similar to the pump of FIGS. 1 and 2, except that in the FIG. 3 pump, the pumping means is, in effect, split into two parts and the engine is inserted therebetween.

The engine valve unit 18 controls the engine and pump unit 214 of FIG. 3 in the same manner that it controls the engine and pump unit 14 of FIGS. 1 and 2. Consequently, a further description is not necessary.

Although exemplary embodiments of the invention have been disclosed for purposes of illustration, it will be understood that various changes, modifications and substitutions may be incorporated in such embodiments without departing from the spirit of the invention as defined by the claims which follow.

I claim:

1. In a fluid operated engine, the combination of: engine piston means reciprocable by an engine-operating pressure differential applied to said engine piston means in opposite directions alternately; engine valve means for applying said engine-operating pressure differential to said engine piston means, including a reciprocable engine valve; means for producing a valve-operating pressure differential which is smaller than said engine-operating pressure differential; and means for applying said valve-operating pressure differential to operate said engine valve.
2. In a fluid operated engine, the combination of: re-

ciprocable engine piston means movable in at least one direction by an engine-operating pressure differential applied to said engine piston means; engine valve means for applying said engine-operating pressure differential to said engine piston means, including a reciprocable engine valve; means for producing a valve-operating pressure differential which is smaller than said engine-operating pressure differential; and means for applying said valve-operating pressure differential to said engine valve in at least one direction.

3. In a fluid operated engine, the combination of: reciprocable engine piston means movable in at least one direction by an engine-operating pressure differential applied to said engine piston means; engine valve means for applying said engine-operating pressure differential to said engine piston means, including a reciprocable engine valve; means for producing a valve-operating pressure differential which is smaller than said engine-operating pressure differential; and means for applying said valve-operating pressure differential to said engine valve in opposite directions alternately.

4. In a fluid operated engine, the combination of: reciprocable engine piston means movable in at least one direction by an engine-operating pressure differential of $P_1 - P_2$ applied to said engine piston means, where P_1 is the supply pressure of an operating fluid and P_2 is the discharge pressure thereof; engine valve means for applying $P_1 - P_2$ to said engine piston means, including a reciprocable engine valve; means for producing a valve-operating pressure differential of Δp which is independent of $P_1 - P_2$; and means for applying Δp to said engine valve in opposite directions alternately.

5. In a fluid operated engine, the combination of: reciprocable engine piston means movable in at least one direction by an engine-operating pressure differential equal to the difference between supply and discharge pressures P_1 and P_2 , respectively, of an operating fluid; engine valve means, including a reciprocable engine valve, for applying $P_1 - P_2$ to said engine piston means; means for producing a valve operating pressure lying between the pressures P_1 and P_2 and differing from one of them by a valve-operating pressure differential Δp which is independent of and smaller than $P_1 - P_2$; and means for applying Δp to said engine valve in opposite directions alternately to reciprocate said engine valve.

6. In a fluid operated engine, the combination of: reciprocable engine piston means movable in at least one direction by an engine-operating pressure differential of $P_1 - P_2$ applied to said engine piston means, where P_1 is the supply pressure of an operating fluid and P_2 is the discharge pressure thereof; engine valve means, including a reciprocable engine valve, for applying $P_1 - P_2$ to said engine piston means; means for producing a valve operating pressure of $P_1 - \Delta p$ where Δp is smaller than and independent of $P_1 - P_2$; and means for applying to said engine valve in opposite directions alternately valve-operating pressures of P_1 and $P_1 - \Delta p$.

7. In a fluid operated engine, the combination of: reciprocable, engine piston means movable in at least one direction by an engine-operating pressure differential of $P_1 - P_2$ applied to said engine piston means, where P_1 is the supply pressure of an operating fluid and P_2 is the discharge pressure thereof; engine valve means, including a reciprocable engine valve, for applying $P_1 - P_2$ to said engine piston means; means for producing a valve operating pressure of $P_2 + \Delta p$ where Δp is smaller than and independent of $P_1 - P_2$; and means for applying to said engine valve in opposite directions alternately valve-operating pressures of P_2 and $P_2 + \Delta p$.

8. In a fluid operated engine, the combination of: reciprocable engine piston means movable in at least one direction by an engine-operating pressure differential of $P_1 - P_2$ equal to the difference between supply and discharge pressures P_1 and P_2 , respectively, of an operating fluid; engine valve means, including a reciprocable engine

valve, for applying $P_1 - P_2$ to said engine piston means; control means for producing a valve operating pressure lying between the pressures P_1 and P_2 and differing from one of them by a valve-operating pressure differential Δp which is independent of and smaller than $P_1 - P_2$, said control means including a source of operating fluid at said valve operating pressure, including a control valve communicating with said source and movable between open and closed positions, including spring means biasing said control valve toward its open position, and including means for applying Δp to said control valve in a direction to bias it toward its closed position; and means for applying Δp to said engine valve in opposite directions alternately to reciprocate said engine valve.

15. In a fluid operated engine, the combination of: reciprocable engine piston means movable in at least one direction by an engine-operating pressure differential of $P_1 - P_2$ equal to the difference between supply and dis-

charge pressures P_1 and P_2 , respectively, of an operating fluid; engine valve means, including a reciprocable engine valve, for applying $P_1 - P_2$ to said engine piston means, control means for producing a valve operating pressure

control means for producing a valve operating pressure P lying between the pressures P_1 and P_2 and differing from one of them by a valve-operating pressure differential Δp , which is independent of and smaller than $P_1 - P_2$, means

26 which is independent of said control means for applying Δp to said engine valve in opposite directions alternately to reciprocate said engine valve; and means incorporated in said control means for increasing Δp with an increase in the viscosity of the operating fluid.

30 hold.

10. In a fluid operated engine, the combination of:
reciprocable engine piston means movable in at least one
direction by an engine-operating pressure differential of
 $P_1 - P_2$ equal to the difference between the supply and
35 discharge pressures P_1 and P_2 , respectively, of an opera-
ting fluid; engine valve means, including a reciprocable
engine valve, for applying $P_1 - P_2$ to said engine piston
means; control means for producing a valve operating
pressure lying between the pressures P_1 and P_2 and differ-
40 ing from one of them by a valve-operating pressure differ-
ential Δp which is independent of and smaller than $P_1 - P_2$,
said control means including a source of operating fluid
at said valve operating pressure, including a control
45 valve communicating with said source and movable be-
tween open and closed positions, including spring means
biasing said control valve toward its open position, and
including means for applying Δp to said control valve in
a direction to bias it toward its closed position; means for
applying Δp to said engine valve in opposite directions
50 alternately to reciprocate said engine valve; and means in-
corporated in said control means for increasing Δp with
an increase in the viscosity of the operating fluid.

11. In a fluid operated engine, the combination of:
reciprocable engine piston means movable in at least one
direction by an engine-operating pressure differential of
55 $P_1 - P_2$ equal to the difference between supply and dis-
charge pressures P_1 and P_2 , respectively, of an operating
fluid; engine valve means, including a reciprocable engine
valve, for applying $P_1 - P_2$ to said engine piston means;
60 control means for producing a valve operating pressure
lying between the pressures P_1 and P_2 and differing from
one of them by a valve-operating pressure differential Δp
which is independent of and smaller than $P_1 - P_2$, said
control means including a source of operating fluid at
65 said valve operating pressure, including a control valve
communicating with said source and movable between
open and close positions, including spring means biasing
said control valve toward its open position, and includ-
ing means for applying Δp to said control valve in a direc-
70 tion to bias it toward its close position; means for apply-
ing Δp to said engine valve in opposite directions alter-
nately to reciprocate said engine valve; and means for in-
creasing Δp with an increase in the viscosity of the oper-
ating fluid, comprising means for applying to said control
75 valve, in direction biasing it toward its open position, a

15

fluid pressure intermediate P_1 and P_2 varying as a function of the viscosity of the operating fluid.

12. In a fluid operated engine, the combination of: reciprocable engine piston means movable in at least one direction by an engine-operating pressure differential of P_1-P_2 , where P_1 is the supply pressure and P_2 is the discharge pressure of an operating fluid; engine valve means, including a reciprocable engine valve movable from one operating position to another, open operating position through an intermediate, governing position, for applying P_1-P_2 to said engine piston means at least when said engine valve is in said other, open operation; means for producing a valve operating pressure lying between the pressures P_1 and P_2 and differing from one of them by a valve-operating pressure differential Δp which is independent of and smaller than P_1-P_2 ; means for applying Δp to said engine valve in opposite directions alternatively to reciprocate said engine valve; and auxiliary valve means for holding said engine valve in said governing position when no load is on said engine piston means.

13. In a fluid operated engine, the combination of: reciprocable engine piston means movable in at least one direction by an engine-operating pressure differential of P_1-P_2 , where P_1 is the supply pressure and P_2 is the discharge pressure of an operating fluid; engine valve means,

16

including a reciprocable engine valve movable from one fully open operating position to another through an intermediate, governing position, for applying P_1-P_2 to said engine piston means when said engine valve is in either of said fully open operating positions; means for producing a valve operating pressure lying between the pressure P_1 and P_2 and differing from one of them by a valve-operating pressure differential Δp which is independent of and smaller than P_1-P_2 ; means for applying Δp to said engine valve in opposite directions alternately to reciprocate said engine valve; and auxiliary valve means controlled by said engine valve means and controlling the application of Δp to said engine valve for holding said engine valve in said governing position with no load on said engine piston means.
